TUBING RACK

Drexel M. Cox, Tuleta, Tex.

Application June 30, 1947, Serial No. 758,083

3 Claims. (Cl. 211—60)

1

This invention relates to tubing racks, and more particularly to an improved tubing rack for supporting well drilling pipe on a derrick.

It is an object of this invention to provide an improved pipe rack of the kind to be more particularly described hereinafter, which is relatively portable so that it may readily be attached to or removed from the platform of a derrick or the like.

Another object of this invention is to provide a tubing rack of this kind having a plurality of spaced apart rods against which and between which the drilling pipes may be supported against the side of the derrick. Pipes held between the rods are securely held in place in any selected order and are held from rolling or piling up against the derrick. The supporting rods are pivotally mounted on a base so that they may be folded back out of the way when all the pipes have been removed from that rod. By folding out of the way, a clear space is provided on the derrick platform so a man may easily reach the next pipes.

A further object of this invention is to provide a tubing rack of this kind having a base which is provided with clamping jaws for attaching the base removably to the planks which form the platform on the derrick. A fixed jaw is formed on the base and a movable jaw is supported on the base, the movable jaw being operated by a lever rockably supported on the base frame, the movable jaw having a certain amount of adjustment to fit various sized planks.

With the above and other objects in view, my invention consists in the arrangement, combination and details of construction disclosed in the drawings and specification, and then more particularly pointed out in the appended claims.

In the drawings,

Figure 1 is a top plan view of a tubing rack constructed according to an embodiment of this invention.

Figure 2 is a transverse section taken on the line 2—2 of Figure 1.

Figure 3 is a longitudinal section taken on the line 3—3 of Figure 1.

Figure 4 is a fragmentary longitudinal section taken on the line 4—4 of Figure 1.

Figure 5 is a fragmentary end elevation taken on the line 5—5 of Figure 1.

Figure 6 is a fragmentary section taken on the line 6—6 of Figure 1.

Referring to the drawings, the numeral 10 designates generally a frame of a derrick used

2

in oil drilling or other drilling operations, using elongated pipes as 11 for the drill rods.

A platform 12 formed of boards 14 is provided at the upper end of the derrick 10 and is supported on the platform forming members 15. The tube rack 16, constructed according to an embodiment of this invention, is adapted to be clamped to the boards 12 for supporting the pipes 11 beside the derrick 10.

10 The tube rack 16 is formed of a rectangular frame 17 having tube supporting rods 18 pivotally supported thereon. An elongated rod 19 is fixed on the frame 17 by engaging the upper end of supporting arms 20 fixed to or formed on a pair of opposite side members of the frame 17.

The rod 19 is supported intermediate the length of the side members of the frame and the pipe supporting rods 18 are rockably mounted on the rod 19. Short sections of tubes or sleeves 21 are loosely carried by the rod 19 in close end abutting relation and the supporting rods 18 are fixed to the sleeves 21 by welding or other suitable fastening devices. In this manner the rods 18 are freely rotatable about the rod 19 on the rack 17.

25 The rods 18 are adapted to extend from one side of the rack 16 so that the tubes or pipes 11 may be supported between adjacent rods 18 in their extended position. As the rods 18 extend from the rack 16 they also extend outwardly from the platform 12. In this position of the rods 18, the tubes 11 are adapted to be engaged between a pair of rods 18 for securely supporting the tubes 11 in selected position. As the tubes or pipes 11 are removed from the rods 18, the rods may be

30 pivoted or rocked about the rod 19 so that the rods 18 are disposed within the confines of the platform 12. In this manner free access may be had to the pipes 11 within the remaining supporting rods 18 by an operator without stepping over the rods 18 from which the tubes 11 have been removed.

The pipe rack 16 is adapted to be clamped onto the platform 12 and is so constructed and arranged that the rack 16 may be installed on any suitable platform when it is needed and may be removed when all the pipes have been used.

35 The construction of this pipe rack is such that it may be manufactured alone and need not be formed as a part of the derrick 10.

40 A fixed jaw member 22 is fixed to or formed on the forward edge of the frame 17 at each end thereof. The fixed jaw member 22 may extend the full length of the forward frame member and is formed of a substantially L-shaped metal bar.

45 The vertical arm 24 of the jaw member 22 is

adapted to overlie the side edge of the outer board 14 and the horizontal arm 25 is adapted to underlie and engage beneath the forward edge of the same board.

A movable jaw member 26 is carried by the rear edge of the tube supporting rack 16. The movable jaw member 26 is formed of a substantially L-shaped jaw having a vertical arm 27 for abuttingly engaging the outer edge of the other end board 14 of the platform 12.

The lower arm 28 is adapted to clampingly engage beneath the board 14 below the arm 27. A forwardly extending arm 29 is fixed to the upper end of the vertical arm 27. The connecting arm 29 extends forwardly and upwardly for pivotal engagement with a lever arm 30 rockably mounted on the frame 17. An elongated pivot rod 31 is loosely supported along the rear edge of the frame 17 by a pair of upstanding supporting members 32 at the opposite ends thereof. The lever arms 30 are fixed to the shaft 31 for rocking movement therewith.

An elongated operating lever 34 is fixed on the shaft 31 intermediate the length thereof for the rotation of the shaft by an operator. A means is provided for locking the lever 34 and shaft 31 in selected position relative to the frame 17. A spring-pressed keeper 35 is carried by the lever 34 and is adapted to engage in the notches 36 of a segmental arcuate locking plate 37. The locking plate 37 is fixed to the rear frame member of the frame 17. A handle 38 is pivotally mounted on the lever 34 for disengaging the keeper 35 from the notches 36 for movement of the lever 34 and shaft 31. The movable jaw member 26 is adapted to engage the side edge of one of the outer boards 14 of the platform 12 and may be moved into clamping engagement by rocking of the control lever 34.

In the use and operation of this tube supporting rack 16, the front jaw member 22 is initially engaged over the forward edge of the forward plank 14. With the control handle 34 moved to a substantially horizontal position so that the movable jaw member 26 is in its extreme adjusted position, the jaw member 26 is disposed as closely as possible in engagement with the rearmost board 14. By rocking the control lever 34 to an erect position or as nearly erect as possible, the crank lever 30 is rocked forwardly carrying with it the movable jaw member 26. The movable jaw member 26 is loosely connected as by a pivot pin 38 to the crank arm 30 and clampingly engages the platform 12 between the fixed jaw member 22 and the movable jaw member 26.

For bracing the extended tube supporting rods 18 in their extended position, a notched plate 40 is fixed to the forward edge of the frame 17 and extends upwardly therefrom. The plate 40 is formed with a longitudinally disposed series

of notches 41 within which the rods 18 are adapted to engage in their extended position. In this manner the rods 18, while supporting the tubes 11, are supported on the frame 17 by both the rod 19 and the plate 40. When the rods 18 are moved to their rearmost position they are raised from the notches 41 and will loosely lie above the shaft 31.

I do not mean to confine myself to the exact details of construction herein disclosed, but claim all variations falling within the purview of the appended claims.

What I claim is:

1. A pipe rack comprising a frame, a rod mounted across said frame intermediate the length thereof, pipe supporting rods pivotally mounted on said first rod, a notched member on said frame parallel to and spaced from said first rod, each of said pipe supporting rods en-

20 gageable in one of said notches in said member in one position and rockable therefrom to an opposite position, a fixed clamping jaw on said frame, a movable clamping jaw carried by said frame coacting with said fixed jaw for clampingly securing said frame on a support therefor, and means rockably carried by said frame for moving said movable jaw.

2. In a pipe rack having a frame and pipe supporting rods pivotally mounted thereon, clamping means carried by said frame for attaching said frame to a support, said clamping means comprising a fixed jaw member on said frame, a shaft rockably mounted on said frame, crank levers on said shaft, a control lever on 30 said shaft, movable clamping jaws pivotally connected to said crank levers, and means for locking said shaft in a selected position.

3. In a pipe rack having a frame and pipe supporting rods pivotally mounted thereon, clamping means carried by said frame for attaching said frame to a support, said clamping means comprising a fixed jaw member on said frame, a shaft rockably mounted on said frame, crank levers on said shaft, a control lever on 40 said shaft, movable clamping jaw members pivotally connected to said crank levers coacting with said fixed jaw members for clamping said rack on a support.

DREXEL M. COX.
